(57) **CLAIM**

The ornamental design new ornamental design for a novel under cabinet/shelf storage rack, as shown and described.

DESCRIPTION

FIG. 1 is an upper front right perspective view of the under cabinet/shelf storage rack.

FIG. 2 is a lower front left perspective view of the rack of FIG. 1.

FIG. 3 is a left side view of the rack of FIG. 1.

FIG. 4 is a right side view of the rack of FIG. 1.

FIG. 5 is a front view of the rack of FIG. 1.

FIG. 6 is a rear view of the rack of FIG. 1.

FIG. 7 is a top view of the rack of FIG. 1.

FIG. 8 is a bottom side view of the rack of FIG. 1.

FIG. 9 is an upper front left perspective view of the rack of FIG. 1 with a box thereon.

FIG. 10 is another upper front left perspective view of the rack of FIG. 1 with boxes thereon.

FIG. 11 is another upper front left perspective view of still another embodiment of the under cabinet/shelf storage rack.

FIG. 12 is another upper front left perspective view of still another embodiment of the under cabinet/shelf storage rack with hook clamps; and,

FIG. 13 is still another upper front left perspective view of the cabinet/shelf storage rack with hook clamps of FIG. 12. The broken lines in FIGS. 9-10, and 13 are for illustrative purposes and form no part of the claimed design.

1 Claim, 10 Drawing Sheets
